(57) **CLAIM**

The ornamental design for a cassette for ophthalmologic apparatus, as shown and described.

DESCRIPTION

This application is related to U.S. design application Ser. No. 29/600,172 entitled "Ophthalmologic Apparatus" that claims the same priority.

This application is related to U.S. design application Ser. No. 29/600,184 entitled "Pedal for Ophthalmologic Apparatus".

The contents of these three related applications are incorporated herein by reference in their respective entireties.

FIG. 1 is a right-front perspective view of a cassette in accordance with the present invention.

FIG. 2 is a left-front perspective view thereof.

FIG. 3 is a right elevation view thereof.

FIG. 4 is a front elevation view thereof.

FIG. 5 is a left elevation view thereof.

FIG. 6 is a back elevation view thereof.

FIG. 7 is a top view thereof; and,

FIG. 8 is a bottom view thereof.

The broken lines depict portions of the cassette for ophthalmologic apparatus that form no part of the claimed design.

1 Claim, 8 Drawing Sheets
